UNITED STATES PATENT OFFICE.

ZACHARA T. MERRILL, OF CHICAGO, ILLINOIS.

WINDOW-DISPLAY.

1,266,297.

Specification of Letters Patent. Patented May 14, 1918.

Application filed July 16, 1917. Serial No. 180,764.

To all whom it may concern:

Be it known that I, ZACHARA T. MERRILL, a citizen of the United States, residing at Chicago, county of Cook, and State of Illinois, have invented new and useful Improvements in Window-Displays, of which the following is a specification.

The object of my invention is to provide a simple device for attracting the notice of the public to window displays and to goods on sale within a store by the movement of a flag or the like. The flag or the like is preferably caused to indicate or spell out brief sentences by dots and dashes of the so-called Morse alphabet.

In other words the flag is automatically moved toward the right and left and to the vertical to indicate the termination of a letter word or sentence. The dots and dashes when understood or properly interpreted may, for example, be read as follows: "Come in and see", "For sale", etc., the first sentence "Come in and see", being indicated as follows:

25 . . . - - . . - - - . . .

the dots being indicated by movements to the left and the dashes indicated by movements to the right, or vice versa, when the flag is retained in the vertical position between one or more side movements to indicate a letter, the flag being held in the vertical position a greater length of time to indicate the close of a word and a sentence. Thus it will be understood that one familiar with the Morse alphabet will naturally be enabled by the movement of the flag to interpret the sentences that are being spelled out, while the movement of the flag will also attract attention of many others who may be unable to interpret such movements as spelling out sentences.

As a means of operating the flag I preferably employ a small electric motor which may be driven either by a small battery or by a dynamo, which dynamo may also be otherwise used for lighting or other purposes.

50 My invention is further explained by reference to the accompanying drawings, in which—

Figure 1 represents a front view of a person holding a flag in a vertical position.

Fig. 2 indicates a side view of a person

holding a flag in a vertical position, partly 55 broken away to show the interior mechanism.

Fig. 3 shows the mechanism by which the flag and staff are thrown toward the left.

Fig. 4 shows the device by which the flag 60 and staff are thrown toward the right while the motor and endless belt driven thereby are moved continuously in the same direction.

Fig. 5 shows a portion of the endless belt 65 with a series of projections thereon, and

Fig. 6 is a vertical section taken on the line 6—6 of Fig. 5.

Like parts are identified by the same reference numerals throughout the several 70 views.

1 is an electric motor of ordinary construction. The required electrical energy is led to the motor 1 from a storage battery or other source of power through the conductor 2, and from thence back to the source of power through the conductor 3. 4 is an endless belt which is supported at one end from shaft 5 and pulley 6, and at its opposite end from the pulley 7, which 80 pulley 7 is fixed on the shaft 8, which is revolubly supported in journal boxes 9, 9. The endless belt 4 is provided with two series of projections 11 and 12. Said projections are adapted to operate the flag staff 14 85 by contacting with the lever 20, secured to the shaft 18, as shown in Figs. 2 and 3, and through the intermediate lever 13 mounted on said shaft 13', said lever 13 contacting with the lever 20' also secured to the shaft 90 18, as shown in Figs. 2 and 4, whereby said staff is inclined both toward the right and left, it being understood that when said projections 11 contact with said lever 20 the upper end of said staff is inclined to the left, 95 reference being had to the observer's left through the partial revolution of the shaft 18 to which the staff is secured, as indicated in Fig. 3, and when thus inclined it is adapted to indicate the dots referred to, and when 100 the movement of the endless belt is communicated to said flag staff through the projection 12, intermediate lever 13, arm 20' and shaft 18 the flag staff is moved toward the right reference being made to the observer's 105 right, as indicated in Fig. 4. The flag 15 used on said staff may be of any kind or color, and may be attached to the upper end

2
of the staff 14 in any convenient manner. I
preferably employ a single endless belt 4,
which belt 4 is provided with two series of
projections 11 and 12, as shown in Figs. 5
5 and 6, whereby when said projections 11 con-
nects with the lever 20, as shown in Fig. 3,
said staff and flag are moved toward the
observer's left and also whereby when said
10 series of projections 12 contact with the in-
termediate lever 13, the upper end of said
staff is moved toward the observer's right,
as shown in Fig. 4, while said projections
are located at longer and shorter distances
15 apart to indicate the end of a letter, word
or sentence.

Said flag staff 14 is connected with the
spiral spring 17 through the shaft 18 and
arm 19, whereby said shaft 14, together with
20 its flag, will be brought to the vertical pos-
ition indicated in Figs. 1 and 2, instantane-
ously as soon as it has been thrown toward
the right or left by the action of any one of
said projections.

It will, of course, be understood that the
25 lower end of said spiral spring 17 is con-
nected at a fixed point, such as shaft 8,
whereby said flag staff 14 will be thrown to
its normal or vertical position by the recoil
30 of said spiral spring 17 acting through said
arm 19 and shaft 18, the arm 19 being set at
the proper angle on the shaft 18 to bring
the staff 14 to the vertical position.

The shaft 8 is driven by the motor 1 in
35 the direction indicated by the arrows in Figs.
3 and 4, through the gear 21 on said shaft
and the pinion 22 of the motor. The projec-
tions 11 and 12 are removably secured to the
40 belt or chain in any suitable manner, screws
23 being shown, thus permitting said projec-
tions to be placed so as to produce any de-
sired word or combination of words.

Having thus described my invention what

I claim as new and desire to secure by Let-
ters Patent, is:—

1. In a device of the described class, the 45
combination of a figure representing a per-
son, a staff, a flag connected with said staff,
said staff being connected with the hands of
the figure represented, an electric motor, and
a spring means for communicating an oscil-
50 latory movement from said motor to said flag
staff, whereby the latter will be caused to
oscillate toward the right and left, said
spring being adapted to stop said shaft as it
reaches the vertical. 55

2. In a device of the described class, the
combination of a figure representing a per-
son, a revoluble shaft extending at right
angles through such figure and terminating
in close proximity to the hands of such 60
figure, a flag staff connected with such shaft,
means for communicating motion in opposite
directions to said revoluble shaft, and from
thence to said flag staff, and a spring adapt-
ed by its downward pull on said shaft to 65
move and retain said staff at the vertical, as
the latter reaches the end of its movement
in opposite directions.

3. In a device of the described class, the
70 combination of an electric motor, an endless
belt, two series of projections connected with
said endless belt, a flag staff, said flag staff
being connected through a revoluble shaft
with an extension adapted to contact with
75 said projections, and a spiral spring connect-
ed with said staff, and adapted by its down-
ward pull to bring said staff to the vertical.

In testimony whereof I affix my signature
in the presence of two witnesses.

ZACHARA T. MERRILL.
